(57) CLAIM

The ornamental design for a spout, as shown and described.

DESCRIPTION

In a preferred embodiment, the nature of this product is as a plumbing fixture in the form of a spout which is primarily useful for washing various parts of the human body.

FIG. 1 is a left, top, front perspective view of a spout embodying my new design;

FIG. 2 is a left side elevational view thereof, the right side elevational view being a mirror image of the left side shown;

FIG. 3 is a front elevational view thereof;

FIG. 4 is a rear elevational view thereof;

FIG. 5 is a top plan view thereof; and,

FIG. 6 is a bottom plan view thereof.

The broken line representations of a mounting structure in FIG. 6 is for the purpose of illustration only and forms no part of the claimed design.
